CONDITION CONTROL DEVICE

Wallace A. Monson, Golden Valley, Minn., assignor to
Honeywell Inc., Minneapolis, Minn., a corporation of
Delaware

Filed Mar. 13, 1968, Ser. No. 10,945

Term of patent 14 years

U.S. Cl. D52—7

Int. Cl. D10—09

Fig. 3

Fig. 4

Fig. 1

Fig. 2

FIGURE 1 is a front view of a condition control device embodying the new design;

FIGURE 2 is a side view as seen from the right side of the device, the left side being substantially a mirror image thereof;

FIGURE 3 is a top view of the device; and

FIGURE 4 is a perspective view of the device with the cover portion in closed position.

The dominant features of the design reside in the portions shown in full lines.

I claim:

The ornamental design for a condition control device, substantially as shown and described.
